UNITED STATES PATENT OFFICE

99,902

DESIGN FOR A BOTTLE

Malcolm N. Stanley, Concord, Mass., assignor to
Felton & Son, Inc., Boston, Mass., a corpora-
tion of Massachusetts

Application September 23, 1935, Serial No. 58,663

Term of patent 14 years

To all whom it may concern:

Be it known that I, Malcolm N. Stanley, a citizen of the United States of America, residing at Concord, in the county of Middlesex and Commonwealth of Massachusetts, have invented a new, original, and ornamental Design for a Bottle, of which the following is a specification, reference being had to the accompanying drawing, forming a part thereof.

Fig. 1 is a front elevational view of a bottle showing my new design; and

Fig. 2 is a sectional view on the line 2—2 of Fig. 1.

The essential features of the design are the

combination of a full swelling body with an upward flare, cask-like in general visual appearance, with a neck relatively short as compared to the body height and a top of greater diameter than the neck having an upwardly sloping wall and being relatively massive and only slightly shorter than the neck.

I claim:

The ornamental design for a bottle substantially as shown and described.

Signed by me at Boston, in the county of Suffolk, and Commonwealth of Massachusetts, this 19th day of September, 1935.

MALCOLM N. STANLEY.
